MANDREL FOR FORMING TUBES

August P. Diescher, Pittsburgh, Pa., assignor to
Diescher Tube Mills, Inc., Pittsburgh, Pa., a
corporation of Delaware

Application January 4, 1936; Serial No. 57,574

7 Claims.

(Cl. 80—13)

This invention relates to mandrels used in making seamless tubes, and more particularly to mandrels having a short working section detachably connected to a mandrel bar.

5 In my Patent No. 2,006,336 and my patent application Serial No. 694,284, filed October 19, 1933, there are shown mills for the cross rolling of tubes in which axial movement of a mandrel relative to the rolls is controlled from 10 the inlet side and from the outlet side, respectively, of the mill. With this type of mill it is desirable, particularly in the production of large diameter tubes, to utilize only a comparatively short portion of the mandrel as a working member. Therefore, it is necessary that only this 15 short working portion be made of heavy wall and have a diameter equal to that required for producing the desired internal diameter of a tube. The rest of the mandrel may be of lighter 20 wall and of smaller diameter. Accordingly, it is desirable to make the mandrel in two parts; that is, a working section detachably connected to a bar or stem, preferably by screw threads, so that the former can be removed and replaced 25 when worn or damaged without having to replace the entire mandrel. However, as the mandrel may under various working conditions be rotated either faster or slower than the tube, there is danger of its working section being 30 screwed from the stem. On the other hand, they should not be connected together in such a manner that it is difficult to separate them when desired.

It is an object of this invention to provide a 35 composite mandrel, having a working section detachably connected to a stem, in which means is provided for locking the two parts together in such a manner that they can not become separated accidentally.

40 Other objects are to provide such a mandrel in which the working section can be easily and quickly detached from the stem when desired, and in which the joint between the working section and stem is substantially water-tight to 45 permit the mandrel to be water-cooled without harmful leakage at the joint.

The preferred embodiment of the invention is 50 illustrated in the accompanying drawing in which Fig. 1 is a side view, partly in section, of a composite mandrel; Fig. 2 is a view similar to Fig. 1 showing the working portion of the mandrel unlocked from its stem; Figs. 3, 4 and 5 are cross sections taken on the lines III—III, IV—IV and V—V, respectively, of Fig. 1; and Fig 6 is an 55 interior view taken on the line VI—VI of Fig. 2.

Referring to Fig. 1 of the drawing, a tubular mandrel stem 1 is connected at its rear end to feed control means, not shown, for controlling its movement axially relative to cross rolls of 60 a tube elongating mill. The feed control means

may be such as disclosed in my above-mentioned patent and patent application. The wall of the stem may be comparatively thin, except at its front or outer end where it is preferably upset to increase its thickness to provide material necessary for jointing and locking purposes. This upset portion is preferably provided with a tapered thread 2 terminating at its front end in a cylindrical sleeve 3 of reduced diameter.

Screwed on the threaded end of the stem is 10 the inner end of a hollow member 4 forming the working section of the mandrel. The outer end of this working section is provided with a reduced portion 5 angular in cross section for receiving a wrench by which member 4 can be 15 screwed on or off the stem without injuring the surface of that member. Sleeve 3 of the stem provides support for the working section and aids in guiding it onto the tapered threads of the stem when the mandrel is being assembled. 20 As member 4 is the only working portion of the mandrel, the stem can have a smaller diameter and a thinner wall and be made of less expensive steel than the working portion, thereby decreasing the cost and weight of the mandrel as 25 a whole, as well as of its manipulating and control apparatus.

Extending axially through the stem and into bore 6 of the working section is a water feed pipe 7 which is centered in the stem by any suitable 30 means, such as by star wheel guides 8 loosely mounted on the pipe between collars 9 secured to the pipe (Fig. 3). Mandrel cooling water flowing into the hollow working section 4 from the outer end of this pipe circulates back through 35 the stem in the space between it and the pipe. To facilitate boring the working section and to provide access for driving out the water pipe in case that becomes necessary, bore 6 extends entirely through the working section with its 40 outer end closed by a screw plug 10 having a projecting angular head adapted to receive a wrench.

It is a feature of this invention that the working section of the mandrel is locked to the stem 45 in such manner as to prevent the two sections from being unscrewed or loosened when in service, the lock being such that it does not interfere with quick and easy removal of the working section from the stem when desired. This is 50 preferably accomplished by making the inside diameter of the working section 4 adjacent the outer end of the tubular stem substantially the same as that of the outer end of the stem, and by providing their interior walls with a plurality 55 of aligned longitudinally extending recesses or grooves 12 and 13 (Fig. 6) that form splines 14 and 16 extending radially inward. Rotatably mounted on and longitudinally movable with water pipe 7 between a pair of collars 17 se- 60

cured thereto, is a generally cylindrical locking member 18 provided about its periphery with a plurality of radial splines or keys 19 extending longitudinally thereof and capable of registering simultaneously with the splines and grooves in both the stem and working section (Figs. 1, 4 and 5), whereby the latter is prevented from being rotated relative to the stem.

The locking member is held in locking position by water pipe 7, the outer end of which is locked against movement axially of the mandrel by any suitable means. As will be seen in Figs. 4 and 5, the grooves in the locking member and in the mandrel sections are deeper than the corresponding splines so as to leave spaces 21 through which water can flow back past the locking member from the bore of the working section. It is unnecessary to have a rotary pipe joint where the outer end of the water pipe is connected to its water supply, because star guides 8 and locking member 18 are loosely mounted on the pipe to permit the mandrel to freely rotate without rotating the pipe.

The working section of the mandrel is unlocked from the stem, to permit them to be separated, by retracting the water pipe to pull the locking member entirely into the stem and out of engagement with the working section, as shown in Fig. 2. In reassembling the mandrel the working section is not screwed up tight on the stem, but is left loose enough to permit it to be rotated sufficiently to bring its splines and grooves into alignment with those of the stem to let the locking member be slid forward into locking position. To make it easier for the keys on the locking member to enter the corresponding grooves in the working section, the ends of the splines and keys are tapered, as shown in Fig. 6.

A mandrel constructed in accordance with this invention is relatively inexpensive because only the short working section need be made of a size and metal capable of withstanding the forces to which it is subjected in use. When in use, the working section is securely locked to the stem so that they can not loosen or come apart accidentally, and the joint is substantially water-tight. The locking means is easily disengaged from the working section, when desired, to permit the latter to be quickly removed from the stem.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A mandrel comprising a stem member, a working member detachably connected to one end thereof, one of said members being provided with an axial bore extending from end to end, means disposed in said bore for locking said members together against rotation relative to each other, and means disposed in said bore for moving said locking means into and out of operative position to lock and release said members.

2. A mandrel comprising a stem member, a working member detachably connected to one

end thereof, one of said members being provided with an axial bore extending from end to end, means slidably disposed in said bore for locking said members together against rotation relative to each other, and means disposed in said bore for sliding said locking means into and out of locking position.

3. A mandrel comprising a stem member, a working member detachably connected to the outer end thereof, one of said members being provided with an axial bore extending from end to end, the portion of the other of said members adjacent said bore being provided with a recess having detents, locking means slidably and non-rotatably disposed in said bore and projecting into said recess for holding said members against rotation relative to each other, and means disposed in said bore and operable from an end thereof for withdrawing said locking means from said recess whereby to permit said members to be rotated relative to each other.

4. A mandrel comprising a tubular stem, a hollow working member detachably connected to one end thereof, a locking member slidably disposed in the stem adjacent said working member and being provided at its periphery with a key, the stem being provided interiorly with a longitudinal groove for receiving said key, said working member being provided interiorly with a key-receiving groove in alignment with said stem groove, and means disposed in said stem for sliding a portion of said key into and out of said working member groove.

5. A mandrel for use in a tube mill, comprising a tubular stem, a hollow working member screwed on the outer end of the stem, the adjoining ends of said stem and working member being provided interiorly with aligned longitudinal grooves, a locking member slidably disposed in said stem and provided at its periphery with a plurality of radial keys registering with said grooves for locking said working member upon the stem, an axially movable water pipe disposed in the stem, and means for connecting said locking member to said pipe whereby the locking member can be withdrawn from said working member by the pipe.

6. A mandrel for use in a tube mill, comprising a tubular stem, a hollow working member screwed on the outer end of the stem, the adjoining ends of said stem and working member being provided interiorly with aligned longitudinal grooves, an axially movable water pipe disposed in the stem, a locking member rotatably mounted on said pipe and slidably disposed in said stem, and means for holding said locking member against movement longitudinally of the pipe, said locking member being provided at its periphery with a plurality of radial keys registering with said grooves for normally locking said working member on said stem.

7. A mandrel comprising a stem member, a working member detachably connected to one end thereof, one of said members being provided with an axial bore extending from end to end, means disposed in said bore for positively locking said members together, and means disposed in said bore for moving said locking means into and out of operative position to lock and release said members, it being necessary for said locking means to be free of one of said members before said members can start to separate.

AUGUST P. DIESCHER.
